W.B. Fahnestock,

Surgical Instrument,

No Printed Specification Available

Patented May 25, 1832.

William B. Fahnstock of Lancaster ... Pennsylvania
Setters Patent.

The schedule referred to in their Setters Patent, and making, part of the same containing a description in the words of the said William B. Fahnstock, himself of his improvement in Surgery called sector tonsillarum.

Be it known that I, William B. Fahnstock of the City of Lancaster, County of Lancaster and State of Pennsylvania, have invented a new and useful improvement in Surgery called sector tonsillarum, and that the following is a full and exact description of the construction and operation of the said Instrument as invented by me. A piece of steel is formed of the length of five and a half inches and the thickness of one fifth of an inch or thereabouts neatly rounded and polished; on the one end thereof is a ring of an inch and a fourth in diameter, and about one sixteenth of an inch in thickness, is split in two equal halves, which split extends down the stem as far as the length of the diameter of the ring - a hole is then drilled up through the centre of the stem to about the size of one third of its diameter.

Another piece of steel is then formed of sufficient thickness to fit in the hole of this stem and on the one end thereof is a circular knife of the diameter above mentioned so thin as to fit in the split of the first mentioned ring.

The upper half of the inner edge of the circular knife is completely sharpened and when put to its place in the split of the first mentioned ring, has the appearance of one perfect ring. The stem of this centre ring, extends through the first mentioned stem about an inch and three quarters; upon this part of a piece of ivory, with a hole in its center through which this passes, is fastened by a small screw at each end forms the handle of the instrument.

By this handle the inner piece of the ring, is drawn down the split in the stem, and will thereby cut off any soft substance that may be placed in the ring, previous to its being drawn down.

The ring, end of this instrument is put in the mouth of the patient, and applied around the tonsil, the inner part of the circle is then drawn back by the hand and removes the tonsil with despatch and safety.

The inventor has formed this instrument in a more simple manner but does not consider it quite as good as the one aforesaid mentioned viz; The stem and ring, may, be split all the way down and kept together by rings, so that the one part will slide past the other, causing the two sections of the ring, to pass each other thereby performing the operation required.

In testimony, that the above is a true specification of my said improvement a, above described I have here set my hand this 25th day of April A.D. 1832.
